UNITED STATES PATENT OFFICE.

BRADLEY WOODHULL, OF DUNMORE, PENNSYLVANIA, ASSIGNOR TO THE SCRANTON STOVE WORKS, OF SCRANTON, PENNSYLVANIA.

DESIGN FOR A STOVE OR RANGE.

SPECIFICATION forming part of Design No. 28,664, dated May 17, 1898.

Application filed March 2, 1898. Serial No. 672,343. Term of patent 14 years.

To all whom it may concern:

Be it known that I, BRADLEY WOODHULL, a citizen of the United States, residing at Dunmore, in the county of Lackawanna and State of Pennsylvania, have invented and produced a new and original Design for Cooking Stoves or Ranges, of which the following is a specification, reference being had to the accompanying drawing.

10 The drawing represents in perspective a stove or range ornamented in accordance with my design.

15 The leading feature of the design consists in the configuration and ornamentation of the parts, as herein shown, described, and claimed.

20 A is the base, and B the legs, of the stove, the base-rail at the front having the central medallion C and covered with a scroll-and-leaf ornamentation, the legs also having the medallion b and covered with a scroll-and-leaf ornamentation, the base-rail at the front being covered with a leaf-and-scroll ornamentation. Above the base-rail is a plain 25 band D, and above this band is the oven-shelf E. This shelf is covered on its top or face with a scroll-and-leaf ornamentation and has a convex edge similarly decorated, the lower edge of the same following the outline 30 of the ornamentation.

35 The oven-door F has a central panel covered with scroll-and-leaf ornamentation, and at the center the panel carries a medallion head or ornamentation e. This central panel is entirely surrounded by scroll-and-leaf ornamentations extending around the margin of the oven-door. To the rear of the oven-door is located the reservoir G, having the central medallion ornamentation f, the remaining 40 surface of the panel being covered with a scroll-and-leaf ornamentation, the lower edge following the outline of the ornamentation.

45 To the front of the oven-door is the fire-door H, having a central medallion H', from which radiate the leaf ornamentations h covering the door. Below this door is a panel I, bearing a scroll i, and below the panel is the ash-pit panel J, bearing the central medallion j and the scroll-and-leaf ornamentation j'.

K indicates the ash-pit door, the lower section of which has the draft-openings k and

the small panels k', bearing scrolls. The upper section of the door is covered with a depending panel or plate K', ornamented with scroll design. Above the ash-pit door is a panel L, bearing the scroll design, and above this panel is the broiling-door M, ornamented with open scrollwork, as shown. Extending along the side of the stove just immediately above the fire-door and oven-door is a line of scroll ornamentations N, and between the reservoir and oven-door is a band of scroll ornamentation N'.

65 The corners O of the stove are of bamboo design, as shown.

Having thus described my invention, what I claim as new, and desire to secure by Letters Patent, is—

70 1. In a design for a stove or range, the design for the base; substantially as herein shown and described.

2. In a design for a stove or range, the design for the oven-door; substantially as herein shown and described.

75 3. In a design for a stove or range, the design for the fire-box door; substantially as herein shown and described.

4. In a design for a stove or range, the design for the panel L; substantially as shown and described.

80 5. In a design for a stove or range, the design for the ash-pit panel J; substantially as shown and described.

85 6. In a design for a stove or range, the design for the ash-pit door; substantially as herein shown and described.

90 7. In a design for a stove or range, the design for the reservoir; substantially as herein shown and described.

8. In a design for a stove or range, the design for the front ash-pit door; substantially as herein shown and described.

95 9. In a design for a stove or range, the design for the broiling-door; substantially as herein shown and described.

10. In a design for a stove or range, the design for the corner; substantially as herein shown and described.

100 11. The design for a stove or range; substantially as herein shown and described.

BRADLEY WOODHULL.
